UNITED STATES PATENT OFFICE.

ROLAND M. GLENN, OF NEW YORK, N. Y., ASSIGNOR TO AMERICAN MAGNESIUM CORPORATION, OF NIAGARA FALLS, NEW YORK, A CORPORATION OF NEW YORK.

TENNIS RACKET OR THE LIKE.

Application filed June 15, 1922. Serial No. 568,373.

To all whom it may concern:

Be it known that I, ROLAND M. GLENN, citizen of the United States, residing at New York, in the county of New York and State of New York, have invented certain new and useful Improvements in Tennis Rackets or the like, of which the following is a specification.

My invention relates to metal game-racket frames, and one of the objects of the invention is to provide such a frame, particularly for tennis rackets, which can be made within the established range of weights for such devices, which will have the necessary stiffness or rigidity, the required elasticity, susceptibility to easy fabrication and good wearing qualities.

In adapting the invention to tennis racket frames, certain established requirements must be met. Such frames are now made almost entirely of wood, the preferred species for this purpose being ash. The continued use of wood, particularly ash, has developed certain standards, including a range of weights, viz, from 12 to 16 ounces, within which such rackets must fall. The practice of using ash has also determined the size of the frame members, as well as their stiffness and elasticity. Wood frames are open to objections, the principal one of which is the tendency to warp, necessitating the keeping of the racket clamped in a press when not in use. Another serious objection is the tendency of wood frames to split. Difficulty is also met in producing good ash frames within the required standard of weights.

In the attempt to overcome the inherent objections to wood frames, various types of metal frames have been experimented with. With this end in view, such frames have been made out of iron, aluminum and light aluminum alloys. While these frames were within the necessary limits of weight and overcame some of the worst objections of the wood frames, they were not successful in actual practice because they were deficient in certain of the other necessary properties which a tennis racket must have and which are possessed by an ash frame. These properties are particularly the necessary elasticity coupled with a certain desirable amount of rigidity.

In ordinary play, a tennis racket is subjected to a wide and variable range of forces,

the effect of which cannot be reasonably foretold. So variable are these factors that it has been found that it is impossible to predict in advance of trying whether a material otherwise having the necessary properties will stand up under the strains to which the racket is subjected.

In stringing the racket and in order that the desired tension may be retained in the strings, the frame cannot be too rigid. On the other hand, the frame must not be too flexible, for it would then be unsuitable for play, as well as not permitting desirable tension of the strings.

I have discovered that when the frame is made out of a suitable section of metallic magnesium or a high magnesium alloy, that all the undesirable properties of an ash frame are eliminated and all the necessary and desirable properties of a wood frame are retained, and in addition an improvement is effected in the desirable properties. So far as I am now aware, no other metal has as yet been discovered that has the combination of properties necessary for its use in this relationship.

Referring to the drawings for a more complete disclosure of the invention:

Figure 1 is a plan view showing a tennis racket embodying the invention;

Figure 2 is a side view;

Figure 3 is a section on the line A—A of Figure 1, and

Figure 4 is a section on the line B—B of Figure 1.

In the tennis racket shown, the bow 2 is formed of an extruded tube of magnesium, or highly magnesium alloy, which is bent into an oval shape with its two ends being extended and brought together to provide handle portions 3. In order to strengthen the frame and to give the handle the proper shape, wooden strips 4 are provided along the sides, a filler strip 5 is provided between the metal handle portions, and a filler block 6 is inserted at the throat of the racket. In stringing the racket, holes 7 are drilled transversely of and through the tube, the holes being slightly rounded off to avoid cutting the strings.

It will be apprehended that the invention is susceptible of a number of embodiments and that the details of construction may be changed and the relative position of cer-

tain of the parts may be altered; the embodiment shown and described therefore is to be considered as indicative only of the principles of the invention. This embodiment, however, has been found to be practical in construction and operation and efficient in use.

As has already been pointed out, the metal which is used may be magnesium, or it may be a high magnesium alloy, as 94% magnesium and 6% aluminum, or any other high magnesium alloy, provided its specific gravity does not greatly exceed the specific gravity of magnesium. The tube is produced by extruding the metal through a die of the desired cross section, and in the embodiment illustrated, the external shape and dimensions of the tube conform to those of the conventional wooden ash frame. In making the frame, a straight extruded piece of tubing may be bent either hot or cold around a form to secure the desired shape of the racket.

Although I have shown an extruded piece of tubing for making the frame out of magnesium metal, it is obvious that other shapes might be employed, provided certain principles are adhered to. Hollow magnesium tubing or equivalent sections have advantages over solid wood frames of the same external dimensions and same weight, when subjected to beam stresses, such as are set up in a tennis racket. Assuming ash wood to have an allowable tensile strength three-tenths that of magnesium, the beam strength of a hollow magnesium beam of the same weight and external dimensions is about 1.8 times that of the wooden beam. Similarly, a hollow magnesium tube of the dimensions considered has nearly $3\frac{1}{2}$ times the beam strength of a solid magnesium rod of the same weight.

Theoretically it is possible to make a hollow section of any but the soft metals which will have the beam strength of a solid wood section of the same weight per unit of length, simply by increasing the size of the hollow section and at the same time decreasing its wall thickness. In practice, however, an increase in size of section over that of the wood frame is undesirable from a playing standpoint. The allowable minimum thickness of wall is determined not only by the necessary rigidity and elasticity of the frame as a whole must have to meet the requirements for proper stringing and the varying conditions of play, but also by the necessary strength the walls themselves must have to withstand local strains due to stringing, accidents or other causes. It is in this respect that I have discovered that magnesium has the necessary combination of physical properties not possessed by any of the metals which have heretofore been tried for this purpose.

The particular advantages of magnesium and high magnesium alloys for devices of this character may be summarized as follows: It permits the use of a section with a large section modulus and large cross section of metal and still with a low weight per unit of length. The large section modulus increases the strength of the section when subjected to beam stresses such as are set up in a tennis racket. The large cross section of metal provides enough thickness of metal around the string holes so that the entrances to these holes can be well rounded off and thereby decrease the risk of breaking the strings at these points. The increased thickness of metal possible adjacent to the holes strengthens the section sufficiently to prevent local distortion under the tension of the racket strings.

The metal usually has an ultimate tensile strength of about 35-45000 lbs. per square inch. This property in conjunction with lightness permits the use of a section, which when subject to the stresses set up in a racket, is 80% stronger than the best solid ash, having the same outside dimensions and the same weight per unit of length.

Magnesium and magnesium alloys are particularly adapted to be formed into shape by extrusion, which thereby permits the production of a hollow tube without any longitudinal joints, which might develop lines of weakness. However, sections either with or without longitudinal joints can be used and still have the advantage that the metal permits a good sectional distribution for strength.

The metal can be readily bent to the proper forms while either hot or cold. The fine machining qualities of magnesium facilitate the necessary drilling of racket frames and such other machine work as may be necessary.

While I have described the production of a hollow section by extruding the metal, it will be understood that the desired cross section of metal may be secured by any of the other well known metal shaping operations to which magnesium is susceptible. By the term "magnesium" in the claims, I comprehend not only the elementary metal but also such magnesium base alloys as lend themselves to similar fabrication treatments.

Although the invention has its greatest utility in connection with tennis rackets, it is obvious that it could also be applied to squash rackets, lacrosse frames and similar game devices.

The terminology hereinabove employed, describing the physical properties of the materials, is in accordance with the approved engineering definitions thereof.

I claim:

1. A tennis racket or like frame made of a section of magnesium having the requisite

beam strength and rigidity as compared to the conventional ash frame of the same weight.

2. A tennis racket or like frame made of 5 a hollow tube of magnesium having the requisite beam strength and rigidity as compared to the conventional ash frame of the same weight and external dimensions.

3. A tennis racket or like frame made of

a hollow tube of magnesium having the 10 requisite beam strength and rigidity as compared to the conventional ash frame of the same weight and external dimensions and having a wall thickness of section which will offer the requisite resistance to deformation from stringing or external blows. 15

In testimony whereof I affix my signature.

ROLAND M. GLENN.
